DESIGN FOR A HANDLE FOR A COCKTAIL SHAKER OR SIMILAR ARTICLE

Omer A. Menard, New York, N. Y., assignor to
S. W. Farber, Inc., Brooklyn, N. Y., a corporation of New York

Application October 16, 1935, Serial No. 59,015

Term of patent 14 years

To all whom it may concern:

Be it known that I, Omer A. Menard, a citizen of the United States, residing at 156 East 47th Street, city of New York, county of New York, and State of New York, have invented a new, original, and ornamental Design for a Handle for a Cocktail Shaker or Similar Article, of which the following is a specification, reference being had to the accompanying drawing, forming part thereof.

I claim:

The ornamental design for a handle for a cocktail shaker or similar article, as shown.

OMER A. MENARD.
